UNITED STATES PATENT OFFICE.

DAVID T. MAY, OF NEW YORK, N. Y., ASSIGNOR TO WESTERN ELECTRIC COMPANY,
INCORPORATED, OF NEW YORK, N. Y., A CORPORATION OF NEW YORK.

PROTECTIVE DEVICE.

1,287,725.

Specification of Letters Patent. Patented Dec. 17, 1918.

Application filed May 25, 1917. Serial No. 170,853.

To all whom it may concern:

Be it known that I, DAVID T. MAY, a citizen of the United States, residing at New York, in the county of New York and State 5 of New York, have invented certain new and useful Improvements in Protective Devices, of which the following is a full, clear, concise, and exact description.

This invention relates to devices for protecting electrical circuits from the destructive effects of abnormal currents or impulses due to lightning discharges, crosses with lines carrying high potential currents and other like causes, and more particularly it 5 relates to an improvement suitable, for example, for use in protective devices of the type commonly known as vacuum lightning arresters in which electrodes separated by a short gap are inclosed in a container exhausted to such a degree that the gap will break down and provide a discharge path at a much lower voltage than it would if placed in air at atmospheric pressure. There is, however, an objection to the vacuum type of arrester in that, following a loss or decrease in vacuum, the degree of protection afforded the line may be decreased to such an extent that protection will no longer be afforded against the power 5 and lighting circuits in common use.

To obviate this defect, there has recently been proposed a vacuum type of arrester having, in addition to the main operating gap, an auxiliary gap which will offer a discharge path and provide protection to the line in case of decrease of vacuum within the container. Such an arrester is shown and described in an application by Stephenson, Serial No. 132,446.

This auxiliary gap is so proportioned with respect to the main gap and the pressure within the container that discharge takes place only across the main gap, so long as the pressure remains constant. However, with a decrease or loss of vacuum, the auxiliary gap, because of its shorter length, provides a discharge path which affords protection to the circuit. It has been found, however, that even under conditions of satisfactory vacuum, the discharge will at times take place across the auxiliary gap and in so doing increase the possibility of maintenance troubles.

It is the object of the present invention to eliminate maintenance troubles resulting

from the discharge occasionally taking place across the shorter gap under conditions of satisfactory vacuum within the container and to accomplish this result, there is provided a construction adapted to place across 60 the auxiliary gap, an electrostatic field in opposition to that tending to cause the gap to break down. It has been found that only a slight neutralization is necessary to prevent arcing at the auxiliary gap under 65 normal conditions and this neutralization is not sufficient to prevent the functioning of the apparatus as desired when the vacuum is impaired.

The several features of this invention may 70 be more clearly understood by reference to the drawings, in which Figure 1 shows diagrammatically the means for providing a neutralizing field across the auxiliary gap, while Fig. 2 shows one method of applying 75 this construction to vacuum arresters of the two-gap type.

Referring more particularly to Fig. 1, the electrodes 4 and 5, separated by the main gap 6, are extended to lie outside of the 80 electrodes 7 and 8 of the auxiliary gap 9. These electrodes are oppositely connected to the electrodes of the main gap, electrode 8 being joined electrically with electrode 4 and electrode 7 with electrode 5. If we assume a difference of potential to exist, tending to cause a discharge to take place across the main gap from electrode 4 to electrode 5, there will also exist a tendency for discharge to take place across the auxiliary gap 90 from electrode 8 to electrode 7, as shown by the arrow in full lines. However, this tendency is partially neutralized by the electrostatic field existing between the extensions of the electrodes 4 and 5, this field being in 95 the direction of the dotted arrow as shown.

In Fig. 2, is shown a vacuum arrester of the double-gap type, equipped with means for providing an opposing field across the auxiliary gap. The evacuated container 10 100 within which the electrodes are mounted, is preferably of glass, formed and evacuated in the usual manner and cemented to a suitable base 11. The electrodes 12 and 13 are two flat pieces of metal formed at one end 105 in the manner shown, to provide the main gap 14 across which the discharge takes place under normal operating conditions. The lower ends of these electrodes are bent out slightly to facilitate securing them to 110

the leading-in wires 15 and 16. Located between the electrodes 12 and 13 from which they are separated by the insulating disks 17 and 18 are the electrodes 19 and 20. These electrodes are separated from each other by a disk of insulating material 21 somewhat larger in diameter than the electrodes and having at its center an opening 22 which acts as the auxiliary air gap in case of decrease of vacuum. Placed on the outside of the electrodes 12 and 13 are the two insulating disks 23 and 24 and binding the whole assembly together are the metal straps 25 and 26 which cross the electrodes and are secured at each end by a bolt, one of these bolts being shown at 27. The electrode 12 is connected electrically to electrode 20 and the electrode 13 is connected electrically to electrode 19. It will thus be seen that the same relationship exists between the two sets of electrodes as is presented in the arrangement shown diagrammatically in Fig. 1.

In case a difference of potential exists between the leading-in wires 15 and 16 of a polarity tending to cause a discharge to pass from electrode 12 to electrode 13, there is also a tendency for discharge to take place across the smaller air gap from electrode 20 to electrode 19. This tendency, however, is to a certain extent neutralized by the electrostatic field set up between the extensions of the electrodes 12 and 13. The desired strength of this electrostatic field is obtained by the proper spacing of the electrodes.

35 What is claimed is:

1. In a protective device, a pair of electrodes so placed that the spark-over voltage is substantially a minimum, a second pair of electrodes so spaced that the spark-over voltage is higher than that of said first pair, and means for partially neutralizing the electrostatic field across said second pair of electrodes.
- 40 2. In a protective device, an evacuated

container, a pair of electrodes so spaced 45 therein that the spark-over voltage is substantially a minimum, a second pair of electrodes so spaced that the spark-over voltage is higher than that of said first pair, and means for partially neutralizing the electrostatic field across said second pair of electrodes.

3. In a protective device, a container, electrodes mounted therein providing a plurality of spark gaps of different lengths, said electrodes being surrounded by gas at substantially the critical pressure of the longer gap, and means for partially neutralizing the electrostatic field across the shorter gap.

4. In a protective device, an evacuated 60 container, a plurality of electrodes therein forming a main gap and an auxiliary gap, the electrodes of said auxiliary gap being connected in opposite electrical relation to the electrodes of said main gap, and so located as to lie within the electrostatic field across the electrodes of said main gap.

5. In a protective device, an evacuated container, a plurality of electrodes providing a main gap and an auxiliary gap, electrodes 70 of said auxiliary gap being positioned to produce an electrostatic field in opposition to that produced by the electrodes of said main gap.

6. In a protective device, an evacuated 7 container, a plurality of electrodes providing a main gap and an auxiliary gap, electrodes of said auxiliary gap being cross-connected to the electrodes of said main gap and so located with respect thereto that the electrostatic field produced by a difference of potential across said auxiliary gap is in opposition to that produced across the electrodes of said main gap.

In witness whereof I hereunto subscribe my name this 22nd day of May A. D., 1917.

DAVID T. MAY.
